DELINTING SCREEN

Archibald H. Davis, Jr., Cleveland, Ohio, assignor
to American Machine and Metals, Inc., East
Moline, Ill., a corporation of Delaware

Application November 18, 1943, Serial No. 510,735

5 Claims. (Cl. 34—82)

1

This invention relates to drying tumblers, and more particularly to the construction and arrangement of the delinting device which forms a part of such drying tumblers.

In drying tumblers such as are used in laundries, the wet clothes are put in a cylinder and dried therein by passing heated air through the cylinder while the latter is rotating. As the clothes fall through the stream of heated air they are dried. As the air passes through the clothes it picks up loose fibers, or lint. For reasons of heat economy it is desirable to circulate the same body of air repeatedly through the cylinders. Each time the air recirculates it picks up additional lint. At the end of the operation cold air is passed through the cylinder to cool the clothes. It is common in the art to provide such drying tumblers, particularly if recirculation of the air is to be used, with a device for separating out the lint which was picked up by the air on its way through the cylinder before the air is allowed to reenter the cylinder. Usually delinting devices take the form of one or several screens made of fine wire mesh through which the air passes. The screens soon clog up, thus impeding the circulation of the air, necessitating the removal of the lint from the screen at short intervals. It has been found difficult to remove the lint from such wire mesh screens, and cleaning devices of various kinds have been suggested for the purpose of brushing off or otherwise removing the fibers which have settled on the screens. Attempts to blow the lint off by reversing the air flow through screen have failed, probably because the lint fibres are often wrapped around the wire of the screens and the air current has twisted the ends of such fibers together.

It is an object of this invention to provide a delinting device which will not permit the lint fibres to become tangled around the elements of this device.

It is a further object of the invention to provide a delinting device composed of open-ended cells which have substantial depth in the direction of the air flow.

A still further object of the invention is to provide a delinting device of ribbon-shaped material, the edges of the ribbon facing the air stream.

Another object of the invention is to provide a delinting device from which lint fibers which have been caught by the device can easily be blown off.

Another object of the invention is the combination in a drying tumbler of a delinting de-

2

vice which prevents the tangling of lint fibers with the parts of the device, with means for changing the direction of the flow of the air through the delinting device.

Still another object of the invention is to provide a self-cleaning screen that is cleaned by shifting the dampers in the tumbler from their recirculating position to their cooling position.

A still further object of the invention is to provide, in a drying tumbler, two alternately functioning air paths, both of which extend from the same side of the fan used for creating the air circulation through the tumbler but lead to opposite sides of the delinting device, the one path leading out to the atmosphere.

Other objects of the invention will appear as the description proceeds, reference being made to the accompanying drawings, in which:

Figure 1 is a sectional elevation of a drying tumbler, illustrating by way of example one embodiment of the invention;

Figure 2 is a plan view of one form of a delinting device according to the invention;

Figure 3 is a section on line 3—3 of Figure 2;

Figures 4 and 5 are plan views of the two modified forms of delinting devices, and

Figure 6 is a fragmental perspective view of another modified form of the delinting device.

Referring first to Figure 1, 10 designates generally a housing, comprising a base 11, a front wall 12, a rear wall 13, and a top 14. Rotatably mounted in housing 10 is a cylinder 53 having foraminous side walls through which air may pass, said walls being generally made of a heavy, coarse wire mesh. The housing 10 further contains a fan or blower 15 adapted to create a forced air circulation through the tumbler, a heater 16, partition walls 17, 18, 19, 20 and 21, three dampers 22, 23 and 24, and a delinting device generally indicated at 25. The device 25 may be arranged between the walls 13 and 17 like a drawer that may be slipped out of the housing 10 through an opening in the rear wall 13. 26 denotes air inlet openings in the top part 14 of the housing 10 which are closable by the damper 24, and 27 is an air outlet arranged near the floor in the rear wall 13. The dampers 22 and 23 may be operable in conjunction. For example, each of these dampers may be pivotally mounted on the wall 17 and attached to a pulley 44, pulley 45, respectively. By means of a crossed belt 46 engaging pulleys 44, 45, the two dampers 22, 23 can be moved together but in opposite directions.

The delinting device 25 which forms an essential part of this invention comprises a series of cells 28. The cells 28 have open ends permitting the passage of air in the direction of the arrows shown in Figure 3 and are of substantial length in this direction. As distinguished from wire mesh screens, the walls or bridges separating the air passages of the delinting device 25, which may be called a "cell screen," have a length in the direction of the air stream which is many times larger than the thickness of the material of which these bridges are formed. The walls of the cells 28 consist of closely-spaced plates facing the air stream with their edges. In the form shown in Figures 2 and 3 a corrugated or crimped ribbon 29 and a flat ribbon 30 are wound spirally around a core 31 in such a manner that the flat ribbon 30 serves as a spacer between consecutive turns of the corrugated ribbon 29. The ribbons 29 and 30 are kept in place in a suitable supporting frame 32.

Figure 4 shows a cell screen wherein corrugated ribbons 34 alternating with flat ribbons 35 are arranged in a rectangular frame 36 whereby again a great number of cells 28 are formed.

Figure 5 illustrates another cell screen of rectangular shape having several layers of corrugated or crimped ribbon 37 arranged in staggered relationship to one another so that the depressed parts 38 of one layer are resting directly upon the upstanding parts 39 of the layer underneath. No flat ribbons between the corrugated ribbons are needed in this case.

The corrugated ribbons shown in Figures 2 and 4 are of regularly undulated shape, whereas in Figure 5 a different type of corrugation is used, the ribbons having relatively wide, flat portions separated by short, upstanding portions. The invention is, however, not limited to any particular shape of crimping or corrugating, nor is the invention limited to cell screens using corrugated ribbons. For example, flat material may be used throughout for forming the cells of the cell screen, as is shown in an example in Figure 6 wherein flat plates 47 which are separated by spacing members 48, form cells 28.

If the length of the cells 28 in the direction of the flow of the air is chosen so that the material of the plates on edge (29 and 30 in Figures 2 and 3, 34 and 35 in Figure 4, 37 in Figure 5, and 47 in Figure 6), forming the bridges between the cells 28, has in every cross sectional plane a perimeter which is greater than the length of the longest fibres which may be reasonably expected to be carried along by the air stream arriving at the screen, the fibers will not be able to wrap completely around those bridges. The lint fibers will be arrested by the plates on edge in the manner indicated at 33 in Figure 3 and at 49, 50 and 51 in Figure 6. That is to say, the lint fibers will either lie across the edges of two or more plates as shown in Figure 6 for the fiber 50, or otherwise will extend into the interior of one or two cells 28 alongside of the walls thereof, as the fibers 33 in Figure 3, or the fibers 49 and 51 in Figure 6. Defined in another way, the fibers will be prevented from tangling if the length of the cells 28 in the direction of the air flow is greater than half the length of these fibers. I prefer to use cells of a length which will take care of fibers of even extraordinary length, although a cell screen which will safely prevent tangling of fibers up to an "ordinary maximum" length may be regarded as satisfactory. A cell screen made of plates or ribbons

having a width of $\frac{1}{8}$ " or more will assure good results for laundry drying tumblers.

Returning now to Figure 1 and following first the air flow taking place when the damper 24 is in the position shown in dotted lines, it will be seen that under the action of the fan or blower 15 air entering the housing 10 through the air inlet openings 26 will pass through the revolving cylinder 53 and the fan 15, the latter discharging the air into a pressure chamber 40. If circulation of the air through the heater 16 and again through the cylinder 53 is desired, the dampers 22, 23, and 24 are brought into the positions shown in full lines. This establishes a communication between the pressure chamber 40 and the space 41 below the cell screen 25. The air following this path between the discharge side of the fan 15 and the cell screen 25 traverses the screen in the upward direction, thus reaching a space 42 above the screen 25 and flowing from there through the heater 16 and a duct 43 formed between the walls 14 and 16 of the housing 10 to the upper end of the cylinder 53. From here the air follows the path already described which is indicated in Figure 1 by arrows shown in full lines, through the revolving cylinder 53, fan 15, chamber 40, space 41, screen 25, space 42, heater 16 and through duct 43 back to the cylinder 53.

When it is desired to feed cold air to the tumbler, for instance to cool the clothes in the cylinder 53 after they have been sufficiently dried by the heated air repeatedly circulated through the tumbler, dampers 22, 23 and 24 are moved into the positions shown by dotted lines. This opens an air path from the discharge end of the fan 15 to the cell screen 25, through space 42 above that screen. Reaching the upper side of cell screen 25 the air passes through it in a downward direction, carrying the lint away from the screen, reaches space 41, and leaves the machine through the outlet openings 27 as indicated by the arrows shown in dotted lines in Figure 1. This outlet 27 may be connected by a duct (not shown) to the outside of the building.

It will be seen that the air must pass through the screen 25 whether the dampers 22, 23 are in the position shown in full lines for recirculation of air heated by heater 16, or in the position shown in dotted lines for the one-way passage of cold air. The two air paths which result from the two alternate positions of the dampers 22, 23, 24 both pass through the screen 25 but traverse the cells of this screen in opposite directions. As has been mentioned before, the flow of air through the cells is upward for recirculation and downward for the discharge of the air from the tumbler through the outlet 27. Lint carried by the heated air arriving at the lower side of the screen 25 during circulation is deposited on this screen. For the reasons pointed out, fibers deposited on the screen 25 are unable to wrap themselves around the bridges of the cell screen. The ends of such fibers cannot twist together, regardless of the strength of the blast of blower 15. Thus, when the dampers are shifted to the position in which they permit the one-way passage of cold air through the tumbler the direction of the air stream through the cell screen 25 is reversed as compared with the direction of the air stream through the cell screen during the recirculation period of heated air. The cold air stream will be able to pick up and remove from the screen the lint previously deposited thereon. In this manner a really effective automatic cleaning of the screen at the

end of each recirculation period is assured, leaving the screen in perfect condition for the next operation of the tumbler.

In Figure 1 the cell screen is shown as located between the discharge end of the fan 15 and the heater 16. It will be understood, however, that the screen may be arranged at some other convenient place within the tumbler, such as between the cylinder 53 and the fan 15 in which case the delinting of the air is taking place before the air enters the fan.

While I have shown and described certain embodiments of the invention, it is understood that these embodiments have been given by way of example only and that various changes, rearrangements and modifications may be made without departing from the spirit of the invention or from the scope of the appended claims.

What I claim is:

1. In a drying tumbler, in combination, a housing having an air inlet and an air outlet, a stationary delinting screen and a fan in said housing, means for forming two air paths alternately leading from the same side of said fan to opposite sides of said delinting screen, said means including dampers controlling said two air paths for reversing the air flow through said stationary screen, said screen comprising a series of adjoining walls forming cells, said walls, in order to prevent the lint fibers arriving at the screen from wrapping completely around the elements of the screen, consisting of closely spaced plates facing the air stream with their edges and extending over a substantial length in the direction of said air stream.

2. In a drying tumbler, in combination, a housing having an air inlet and an air outlet, a stationary delinting screen and a fan in said housing, means for forming two air paths alternately leading from the same side of said fan to opposite sides of said delinting screen, said means including dampers controlling said two air paths for reversing the air flow through said stationary screen, said screen comprising a series of adjoining walls forming cells, said walls, in order to prevent the lint fibers arriving at the screen from wrapping completely around the elements of the screen, being of a length in the direction of the air stream many times greater than the thickness of said walls.

3. In a drying tumbler, in combination, a housing having an air inlet and an air outlet, a stationary delinting screen and a fan in said housing, means for forming two air paths alternately connectable to the same side of said fan to opposite sides of said delinting screen, said means including dampers controlling said two air paths for reversing the air flow through said stationary screen, said screen comprising a series of adjoining cells, formed at least partly by adjacent layers of corrugated ribbon facing the air stream with its edges.

4. In a machine for drying clothes of the kind in which each batch of clothes is subjected first to heated air recirculating repeatedly through

the machine and then to air passing through the machine once and out to the atmosphere, in combination, a housing, an air passage therein, dampers in the housing adapted to pass the recirculated air through the passage in one direction and the air passing to the atmosphere through the same passage in the other direction, a stationary delinting screen in the passage, said delinting screen having plates extending in the direction of the air stream over a substantial length whereby the lint deposited during recirculation on the screen is automatically removed during the period when the dried clothes are cooled by air flowing to the atmosphere, an air path for the flow in one direction of the recirculating air, a second air path for the flow in the opposite direction of the air that is not recirculated, said stationary delinting screen intercepting both said air paths, dampers controlling said two air paths for reversing the air flow through said screen, in which screen the lint is caught on the edges of said plates during the period of recirculation, and is automatically blown off when the air current is reversed.

5. In a drying tumbler, in combination, a housing having an air inlet and an air outlet, a stationary delinting screen and a fan in said housing, means for forming two air paths alternately leading from the same side of said fan to opposite sides of said delinting screen, said means including dampers controlling said two air paths for reversing the air flow through said stationary screen, said screen comprising a series of adjoining cells formed by several layers of corrugated ribbon facing the air stream with their edges, the corrugations in said layers being arranged in staggered relationship to those in adjacent layers so that the depressed parts of one layer rest directly upon upstanding parts of an adjacent layer.
